UNITED STATES PATENT OFFICE.

WESLEY MARVIN POPE, OF WASHINGTON, DISTRICT OF COLUMBIA.

DESIGN FOR A PENNANT.

Application filed January 26, 1923. Serial No. 4,995. Term of patent 3½ years.

To all whom it may concern:

Be it known that I, WESLEY MARVIN POPE, a citizen of the United States, residing at Washington, in the District of Columbia, have invented a new, original, and ornamental Design for Pennants, of which the following is a specification, reference being had to the accompanying drawing, forming part thereof.

The figure is a plan view of a pennant, showing my new design.

I claim:

The ornamental design for a pennant, as shown.

WESLEY MARVIN POPE.
